Filed Sept. 18, 1962, Ser. No. 71,740

Term of patent 14 years

(Cl. D48—32)

FIGURE 1 is a front elevational view of a combined anchor and bow light incorporating my new design;

FIGURE 2 is a top plan view of the combined anchor and bow light shown in FIGURE 1;

FIGURE 3 is a rear elevational view of the combined anchor and bow light shown in FIGURE 1;

FIGURE 4 is a side elevational view of the combined anchor and bow light shown in FIGURE 1;

FIGURE 5 is a bottom plan view of the combined anchor and bow light shown in FIGURE 1;

FIGURE 6 is a perspective view, on a somewhat reduced scale, taken from the top, rear and one side of the combined anchor and bow light shown in FIGURE 1; and

FIGURE 7 is a perspective view taken from the top, front and other side of the combined anchor and bow light shown in FIGURE 1.

The dominant features in my design reside in the portions shown in full lines.

I claim:

The ornamental design for a combined anchor and bow light, as shown and described.
